UNITED STATES PATENT OFFICE

ERNEST O. FREDERICS, OF NEW YORK, N. Y., ASSIGNOR TO E. FREDERICS, INC., OF NEW YORK, N. Y., A CORPORATION OF NEW YORK

HAIR TREATING DEVICE

Application filed March 25, 1926. Serial No. 97,363.

This invention relates to a pad of improved construction for use in connection with permanent hair-waving methods.

It is an object of the invention to provide a device of this character which will afford a maximum of protection against injury to the person whose hair is being treated, and which will expedite and improve the results of such treatment.

20 A further object is that of furnishing a device of this character which may be readily shipped and handled and which will always be in usable condition, the pad being of such a nature that its several parts may be readily 15 and economically constructed and assembled.

Other objects of the invention will in part be obvious and will in part appear hereinafter.

The invention accordingly comprises an 20 article of manufacture possessing the features, properties and the relation of elements which will be exemplified in the article hereinafter described and the scope of the application of which will be indicated in the 25 claims.

For a fuller understanding of the nature and objects of the invention reference should be had to the following detailed description taken in connection with the accompanying 30 drawings, in which:

Figure 1 is a front view of one form of pad embodying the improved construction of the present invention;

Fig. 2 is a transverse sectional view taken 35 along the lines 2-2 and in the direction of the arrows of Fig. 1;

Fig. 3 illustrates the pad in partially rolled condition, certain of the outer portions thereof being broken away to disclose the underlying construction;

Fig. 4 is a sectional view of the device, showing the same in applied position;

Fig. 5 is a view similar to Fig. 1, but showing a slightly different form of the pad; and

45 Fig. 6 is a view taken along the line 6-6 and in the direction of the arrows of Fig. 5.

As aforesigned, a pad of this nature is for use in the treatment of hair, and is particularly intended to be employed in connection 50 with permanent waving. In such use, and

as has been shown, for example, in Fig. 4, a tress of hair 10 is coiled in any suitable manner, as at 11, around a spindle 12, the pad being placed around the coiled tress in the form of a tube. Prior to its application 55 to the hair the pad or portions thereof may be dampened, and the whole may be disposed within a suitable tube form of heater.

With reference to Figs. 1, 2 and 3 it will be noted that the hair-treating portion of 60 the pad preferably comprises a sac or envelope 13 of perforate material, for example, gauze. This receptacle is filled with a layer of suitable hair-treating material. While this material may be of any desirable character, it is preferred in the present instance to employ powdered borax 14, and in order to prevent the displacement of this substance within the receptacle the body of the latter 65 may be provided with lines of stitching 15, 70 which will serve to prevent this occurrence.

Arranged adjacent the outer face of the envelope is a layer of gas-impervious material 16, and a layer of packing material 17 may be interposed between the material 16 75 and the envelope 13. A suitable form of paper may be utilized to provide the sheet 16, and the strip 17 may be formed of flannel, it being here noted that two edges of these sheets are arranged substantially in line with 80 each other and that the envelope 13, while being secured thereto, preferably has a portion of its body extending beyond one of the side edges of these sheets.

Arranged beyond the outer face of the 85 sheet 16 is a layer of material 18, which, while transmitting heat, will not be readily destroyed by the action of the same. To this end, foil having a high melting point may be employed, for example, copper or 90 silver foil lends itself to this purpose.

With reference to the form of pad shown in Figs. 5 and 6, the layer 19 of foil is of less area than the sheet 18 shown in the preceding views, and the side edge of this layer is 95 not in line with the forward edges of the sheets which are secured to its inner face, the width of the strip 19 being in the present exemplification approximately equal to the length of the heater or tube within which 100

the pad is to be disposed. Also, while in this form of device sheets of fireproof and impervious materials 19 and 21 respectively are employed, the latter is not directly secured to the inner face of the sheet 19, but, rather, a layer of insulating material 22 is interposed between these elements and carries a strip 20 of packing material. The sheet 22 may be formed of cloth which has been impregnated with a suitable fireproofing substance, or the inherent characteristics of the sheet may be such that it has these qualities.

In both of the illustrated forms of the invention the several component elements may be secured to one another in any manner most desirable, and after the tress of hair has been arranged around the spindle, the envelope or container 13 is in the present instance moistened and coiled around the hair. Due to the arrangement of the pad parts it will be understood that a continued coiling of the pad will result in the layer of impervious material completely enclosing the envelope due to the fact that the rear edge of this sheet overlaps the rear edge of the envelope. Likewise, the strips of packing material will bear tightly against the outer surface of the strand of hair, and if, as in the present exemplifications, the rear edges of these strips extend beyond the rear edges of the impervious sheets it will be understood that a surplus of material will be provided at this point to assure of an adequate packing, preventing the ready escape of gases at this point. This escape will be likewise prevented by the heat-conducting and resistant sheet or strip 18. While this sheet, as well as the sheet 19, will serve to readily conduct the heat from the member which encloses the pad and thus cause the substance within the envelopes to give off gases which will expedite the treatment of the hair, they will both be flexible and readily conform to any desired shape. In the case of the former sheet, i. e., 18, they will also serve to prevent the parts, and particularly the sheet 16, from smoldering, in the event of excessive heat, due to the fire-resistant qualities and for the reason that it will prevent air coming in contact with the coiled hair. In the case of the second form of the invention the sheet of fireproof material 22 will prevent any danger in this connection, it being noted, as in Fig. 4, that these elements may be retained in tight contact with the hair by a clip or any other suitable form of member 23.

It will be appreciated that a pad is provided by means of which the hair may readily be treated in an efficacious manner and without danger of injury to the person. Furthermore, the parts of this pad may be readily constructed and assembled, and an article constructed within the terms of the

present invention may be frequently handled or stored over long periods of time without losing any part of its desirable properties.

Thus, among others, the objects of this invention have been accomplished, and since certain changes may be made in the above article, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. As an article of manufacture, a hair-treating pad, including a container for hair-treating substance, and a sheet of insulating material arranged beyond said container and secured thereto, said sheet extending beyond the rear edge of said container and terminating at a point short of the forward edge thereof.

2. As an article of manufacture, a hair-treating pad, including a container for hair-treating substance, and a sheet of heat-conductive and fire-insulating material arranged adjacent the outer face of said container and secured thereto, said sheet having its rear edge extending materially beyond the rear edge of said container, its forward edge terminating at a point short of the forward edge of said container.

3. As an article of manufacture, a hair-treating pad, including a container for hair-treating substance, a sheet of material substantially impervious to gases arranged beyond the outer face of said container, said sheet having its rear edge extending beyond the rear edge of said container and being secured thereto, and a strip of packing material interposed between said sheet and said container and extending beyond the side edge of the latter.

4. As an article of manufacture, a hair-treating pad, including a container for hair-treating substance, a sheet of material substantially impervious to gases arranged beyond the outer face of said container, said sheet having its rear edge extending beyond the rear edge of said container and being secured thereto, and a strip of packing material interposed between said sheet and said container and extending beyond the side edge of the latter, the rear edge of said latter strip extending beyond the rear edge of said sheet.

5. As an article of manufacture, a hair-

- treating pad, including a container for hair-treating substance, a sheet of material substantially impervious to gases disposed adjacent the rear face of said container, a strip 5 of packing material interposed between said sheet and said container, and a sheet of fire-proof and heat-conducting material arranged beyond said last-named sheet.
6. As an article of manufacture, a hair-treating pad, including a container for hair-treating substance, a sheet of material substantially impervious to gases disposed adjacent the rear face of said container, a strip 10 of packing material interposed between said sheet and said container, and a sheet of fire-proof and heat-conducting material arranged beyond said last-named sheet, the forward edges of said sheets and strip terminating at a point short of the forward edge of said container, the rear edges of all of the same extending to points beyond the rear edge of said container. 15
7. As an article of manufacture, a hair-treating pad, including a container for hair-treating substance, a sheet of material substantially impervious to gases disposed adjacent the rear face of said container, a strip 20 of packing material interposed between said sheet and said container, and a sheet of fire-proof and heat-conducting material arranged beyond said last-named sheet, the forward edges of said sheets and strip terminating at a point short of the forward edge of said container, the rear edge of said strip extending beyond the rear edge of said first sheet, and the rear edge of said last sheet extending beyond the rear edge of said strip. 25
8. As an article of manufacture, a hair-treating pad, including a container for hair-treating substance and a sheet of heat-conductive and heat-resistant material arranged beyond said container and secured thereto, said sheet extending beyond the rear edge of said container and terminating at a point 30 short of the forward edge thereof. 35
9. As an article of manufacture, a hair-treating pad, including a container for hair-treating substance and a sheet of flexible metal arranged beyond said container and secured thereto, said sheet extending beyond the rear edge of said container and terminating at a point short of the forward edge thereof. 40
10. As an article of manufacture, a hair-treating pad, including a container for hair-treating substance and a sheet of metallic foil having a high melting point arranged beyond said container and secured thereto, said sheet extending beyond the rear edge of 45 said container and terminating at a point short of the forward edge thereof. 45
11. As an article of manufacture, a hair-treating pad, including a container for hair-treating substance and a sheet of material 50 substantially impervious to gases arranged
- beyond said container and secured thereto, said sheet extending beyond the rear edge of said container and terminating at a point short of the forward edge thereof. 55
12. As an article of manufacture, a hair-treating pad, including a container for hair-treating substance and a sheet of fire-proof material arranged beyond said container and secured thereto, said sheet extending beyond the rear edge of said container and terminating at a point short of the forward edge thereof. 60
- In testimony whereof I affix my signature.
